United States Patent Office

Des. 229,478
Patented Dec. 4, 1973

229,478

ESCUTCHEON

Raymond U. H. Tegner, Rockford, Ill., assignor to
Amerock Corporation, Rockford, Ill.

Filed June 1, 1971, Ser. No. 149,121

Term of patent 14 years

Int. Cl. D8—09

U.S. Cl. D8—179

FIG. 14.FIG. 15.FIG. 16.FIG. 17.FIG. 18.

FIG. 19.

FIG. 20.

FIG. 21.

FIG. 22.

FIG. 23.

FIG. 24.

FIG. 1 is a front view of an escutcheon wherein my design resides in a switch plate.

FIG. 2 is a side view of the plate as seen from the right of FIG. 1.

FIG. 3 is a sectional view taken along the line 3—3 in FIG. 1.

FIG. 4 is an end view as seen from the bottom of FIG. 1.

FIG. 5 is a sectional view taken along the line 5—5 in FIG. 1.

FIG. 6 is a sectional view taken along the line 6—6 in FIG. 1.

FIG. 7 is a sectional view taken along the line 7—7 in FIG. 1.

FIG. 8 is a fragmentary sectional view taken along the line 8—8 in FIG. 1.

FIG. 9 is a front view of an escutcheon wherein my design resides in an electrical receptacle plate, the side and end views being the same as FIGS. 2 and 4, the sections being the same as shown in FIGS. 5 and 8 and the edge configurations being the same as shown in FIGS. 6 and 7.

FIG. 10 is a fragmentary sectional view taken along the line 10—10 in FIG. 9.

FIG. 11 is a front view of an escutcheon wherein my design resides in an escutcheon plate for a door knob, the side and end views being the same as FIGS. 2 and 4, the sections being the same as shown in FIGS. 5 and 8 and the edge configurations being the same as shown in FIG. 6.

FIG. 12 is a fragmentary sectional view taken along the line 12—12 in FIG. 11.

FIG. 13 is a sectional view taken along the line 13—13 in FIG. 11.

FIG. 14 is a front view of an escutcheon wherein my design resides in a combined electrical switch and receptacle plate, the side view being the same as FIG. 2, the edge configurations being the same as shown in FIGS. 3, 5, 6 and 7.

FIG. 15 is an end view as seen from the bottom of FIG. 14.

FIG. 16 is a fragmentary sectional view taken along the line 16—16 in FIG. 14.

FIG. 17 is a fragmentary sectional view taken along the line 17—17 in FIG. 14.

FIG. 18 is a fragmentary sectional view taken along the line 18—18 in FIG. 14.

FIG. 19 is a front view of an escutcheon wherein my design resides in a triple switch plate, the edge configurations being the same as shown in FIGS. 3, 5, 6, 7, 16, 17 and 18.

FIG. 20 is an end view of the switch plate as seen from the bottom of FIG. 19.

FIG. 21 is a side view of an escutcheon wherein my design resides in an escutcheon plate for a garment hook, with the end view being the same as shown in FIG. 4 but on a smaller scale and with the edge configurations being the same as shown in FIGS. 3, 5, 6, 7 and 8 except on a smaller scale.

FIG. 22 is a plan view taken along the line 22—22 in FIG. 21.

FIG. 23 is a side view of an escutcheon wherein my design resides in an escutcheon plate for a door stop, with the end view being the same as shown in FIG. 4 but on a smaller scale and with the edge configurations being the same as shown in FIGS. 3, 5, 6, 7 and 8 except on a smaller scale.

FIG. 24 is a plan view taken along the line 24—24 in FIG. 23.

FIG. 25 is a side view of an escutcheon wherein my design resides in an escutcheon plate for a tissue holder with the end view the same as shown in FIG. 20 and the edge configurations the same as shown in FIGS. 3, 5, 6, 7, 16, 17 and 18.

FIG. 26 is a plan view taken along the line 26—26 in FIG. 25.

The portions shown in broken lines are for purposes of illustration only.

I claim:

The ornamental design for an escutcheon, as shown and described.
